UNITED STATES PATENT OFFICE

2,278,116

MECHANICAL STRIPPING DEVICE

Peer D. Nielsen, Lorain, Ohio, assignor to National Tube Company, a corporation of New Jersey

Application December 31, 1940, Serial No. 372,629

6 Claims. (Cl. 22—95)

The present invention relates to improvements in stripping devices which, while not limited thereto, are well suited for stripping ingots from their molds or core bars from a poured ingot mold flask assembly.

The invention provides improved means to enable the removal of an ingot from its mold, or the removal of a core arbor from a poured ingot mold assembly. However, the device may be used in other environments, as will be apparent from the following disclosure.

One object of the invention is to provide a stripping device which will translate the weight of the object being stripped into the force required for stripping by the provision of a lever system, so constructed and arranged as to require very little headroom for its operation.

Another object is to provide a compactly assembled lever system for use in a stripping mechanism which, when suspended from an overhead traveling crane, will be capable of easy, quick, and reliable operation in congested locations.

The above and other features of the invention as defined with particularity in the appended claims, will be fully apparent from consideration of the following detailed disclosure when read in connection with the accompanying drawings, in which:

Figure 1 is a side elevation of the stripping device;

Figure 2 is an end elevation thereof;

Figure 3 is a view showing the stripper suspended from an overhead crane and engaged in initial stripping position with an ingot and ingot mold;

Figure 4 is a similar view showing the stripper suspended from an overhead crane and engaged in stripping position with a poured ingot mold flask assembly;

Figure 5 shows the position of the parts at an intermediate stage in the operation;

Figure 6 shows the position of the parts at the end of the stripping stroke.

Very large forces are required to initiate stripping of ingots from their molds, or core bars from a poured ingot mold flask assembly. However, after initially breaking the ingot loose from the mold, or the core bar loose from the poured ingot mold flask assembly, a considerably reduced force is sufficient to continue stripping. The reason for the reduction in stripping force required for stripping after the ingot or core bar has broken loose and moved a small distance, is that core bars and ingots are tapered, so that, with continued movement in the strip-

ping operation, clearance is provided to facilitate easy withdrawal of the mold from the ingot or the ingot mold flask assembly from the core bar. However, irregularities of the surface of the ingot or core bar and the confining ingot mold or ingot mold flask assembly are usually of such a magnitude that, in addition to providing a very large force to break the ingot or core bar loose to initiate movement, a stripping force of lower magnitude must still be applied for a length of stroke sufficient that the increase in dimensions of the confining ingot mold or ingot mold flask assembly, as provided by the taper, is sufficient to permit easy withdrawal of the ingot or core bar.

Heretofore it has been common practice to construct stripping devices with a stripping force sufficient to break the object loose from the mold, this same force being maintained available for the entire stripping stroke. Stripping forces for this purpose are commonly developed by hydraulic pushers, motor operated screws, motor operated cable systems, or simple lever systems, no attempt heretofore having been made to take advantage of the fact that a considerably lesser stripping force is required once stripping movement is initiated.

Advantage of this difference in stripping force requirement is taken in carrying out this invention for the purpose of achieving compactness in construction and minimum requirement of headroom for successful operation.

The stripping device comprises a spreader 1 which is suspended from hook H of a crane C, 35 a body or housing 2 which provides a support for the various levers and contains the various fulcrums around which the levers move, connecting rods 3 which link the lever system to the spreader 1, arms 4 and 5 which provide an adjustable means of attaching the stripping device to the cheek section of an ingot mold flask assembly or to an ingot mold, and a block or bullnose 6 for engaging the ingot core arbor or other object to be stripped.

45 The lever system includes two levers 7 and 9 and connecting rod 8. The lever 7 is provided with pins 10 and 11 disposed to be engaged in grooves 15 and 16 in body section 2. Lever 9 is provided with a fulcrum at point 12. The connecting rod 8 connects levers 7 and 9 together at points 14 and 13 respectively. The outer end of lever 9 is attached to connecting rod 8 at point 18 and the outer end of lever 7 is connected to arm 4 at point 17.

50 The improved stripping device is specifically

constructed to translate the weight of the object being stripped into the stripping force required to accomplish stripping. It is thus particularly suited for stripping such heavy objects as ingots from ingot molds and core bars from ingot mold flask assemblies where the weight involved is considerable and of sufficient magnitude to provide, within the limits of the capacity of the device for multiplying this weight, sufficient force to accomplish stripping.

A particular advantage inherent in the novel device herein claimed is that no outside source of power is required to develop the force necessary for stripping, all the force required being developed from the weight of the object being stripped. The lever system of the stripping device is designed with a mechanical advantage which multiplies the weight of the object being stripped and translates this weight into stripping force sufficient to accomplish stripping without the need for any outside source of power. Furthermore, the load on the crane or similar device on which this stripping device is suspended while in use is entirely independent of the stripping force developed, the load on the crane never exceeding the combined weight of the stripping device and the objects to which it is attached for stripping.

Another particular advantage of the novel stripping device as defined in the claims, is the compact construction which facilitates its use in the very congested areas where stripping operations must frequently be performed. Although the same stripping force could be developed by a stripper having two single lever arms, such construction would necessitate single lever arms of such length, for the same developed force, as to make the device cumbersome and awkward to handle and would thereby require considerable space for satisfactory operation. The provision of means for shifting the fulcrum in one of the lever arms has the very desirable advantage of reducing the headroom required for operation. This is an important consideration where it is desired to strip objects of considerable length, using cranes with limited headroom for operating the stripping device. Figures 4, 5, and 6 illustrate this feature. Figure 4 shows the stripping device attached to a poured ingot mold flask assembly at the beginning of the stripping stroke.

Figures 5 and 6 are similar illustrations, Figure 5 showing the position of the lever arms at that interval or stage of the stripping stroke where lever 7 has just completed its movement about fulcrum 10 and is about to continue movement about fulcrum 11, and Figure 6 showing the position of the lever arms at the end of the stripping stroke.

In Figures 4, 5, and 6, the scale of the drawings shows that a mechanical advantage of $2\frac{1}{2}$ to 1 is indicated for lever 9 about fulcrum 12. Similarly a mechanical advantage of 3 to 1 is indicated for lever 7 about fulcrum 10 and a mechanical advantage of 1 to 1 of this same lever 7 about fulcrum 11. It is to be understood, of course, that the mechanical advantages recited are merely for the purpose of illustration as mechanical advantages of any magnitude desired can be used. In Figure 4, with the stripping device in the starting position, the over-all mechanical advantage of the lever system is $(3 \text{ to } 1) \times (2\frac{1}{2} \text{ to } 1) = 7\frac{1}{2}$ to 1. This mechanical advantage is maintained during the initial stripping stages or until the position illustrated in Figure 5 is reached. Upon further stripping

movement, the lever 7 thereupon begins to move about pin 11 as a fulcrum. At this stage of the stripping stroke the overall mechanical advantage of the system is $(1 \text{ to } 1) \times (2\frac{1}{2} \text{ to } 1) = 2\frac{1}{2}$ to 1.

As has previously been pointed out, the force required for stripping after stripping is initiated is much reduced, and under the present invention advantage is taken of this fact to reduce headroom requirements for the stripping operation.

A stripper of the proportions indicated in the various figures and with mechanical advantage of levers recited in the foregoing paragraph has a stripping movement of 2 inches between the positions shown in Figures 4 and 5. Coincident with a stripping movement of 2 inches, the spreader bar 1 is raised $7\frac{1}{2} \times 2 = 15$ inches. Similarly, between positions shown in Figures 5 and 6, the stripping movement is 6 inches and, as the

mechanical advantage at this stage of the stroke is $2\frac{1}{2}$ to 1, the coincident movement of spreader bar for a 6-inch stripping stroke is $2\frac{1}{2} \times 6 = 15$ inches. Thus it is seen that with the double fulcrum multiple lever system I can accomplish a stripping stroke of 8 inches with a rise of the spreader bar of 30 inches whereas, had a mechanical advantage of $7\frac{1}{2}$ to 1 been maintained for the entire stripping stroke of 8 inches, the rise of the spreader bar would have been $7\frac{1}{2} \times 8'' = 60$ inches.

In the example referred to, the described construction has resulted in a conservation of 30 inches of spreader bar travel to secure the same stripping stroke as could have been accomplished had the mechanical advantage of $7\frac{1}{2}$ to 1, which is required to initiate stripping, been acting over the entire stripping stroke. Thus the headroom requirements for stripping has been reduced by a similar amount, namely, 30 inches.

The stripping forces developed by this stripping device when having the proportions above recited are such that if the object being stripped has a weight of 10 tons, the stripping force developed in that portion of the stroke having a mechanical advantage of $7\frac{1}{2}$ to 1 is 75 tons and the force developed in that portion of the stroke having a mechanical advantage of $2\frac{1}{2}$ to 1 is 25 tons.

While I have described quite precisely the details of a specific embodiment of the invention herein illustrated, it is to be understood that the drawings and description are to be interpreted in an illustrative rather than a limiting sense, since various modifications may be made without departure from the invention as defined in the appended claims.

I claim:

1. A stripping device for separating nested objects from one another, comprising a spreader supported from overhead, a frame movable relatively thereto and having an abutment for engagement with one of the objects to be separated, a multiple lever system carried by the frame and arranged so as to provide a dual set of fulcrums which come into play at different times to effect a change in the mechanical advantage of the system whereby the magnitude of the stripping force exerted to separate said nested objects is greatest during the initial stage of the stripping stroke and decreases thereafter.

2. A stripping device for separating nested objects from one another, comprising a spreader supported from overhead, a frame movable relatively thereto and having an abutment for engagement with one of the objects to be separated, and a multiple lever system carried by the frame

and arranged so as to provide a dual set of fulcrum points for certain of said levers of the system whereby the magnitude of the stripping force exerted to separate said nested objects is greatest during the initial stage of the stripping stroke and decreases thereafter.

3. A stripping device for separating nested objects from one another, comprising a spreader supported from overhead, a frame movable relatively thereto and having an abutment for engagement with one of the objects to be separated, and a multiple lever system carried by the frame and having one connecting member coupled with said spreader and another engaged with the other of said nested objects, there being means provided for shifting the fulcrum points of certain levers of the system so as to provide the greatest mechanical advantage at the initial stage of the stripping stroke with a decreasing mechanical advantage as the stripping stroke proceeds.

4. A stripping device for separating nested objects from one another, comprising a spreader supported from overhead, a frame movable relatively thereto and having an abutment for engagement with one of the objects to be separated, and a multiple lever system carried by the frame, one connecting member coupling said system with one of said nested objects, another connecting member connecting said system with said spreader, said system including a lever carrying two fulcrum pins and said frame having two fulcrum notches adapted for alternate coaction with said two pins, whereby the mechanical advantage of the system is greatest during the in-

ital stage of the stripping stroke and decreases as the stripping stroke proceeds.

5. A stripping device of the character described, comprising a member adapted to be suspended from an overhead crane, a frame having an object-engaging portion for coaction with one of two objects to be separated, a pair of fixed-fulcrum levers mounted on said frame and having respective links connecting them with said member, a pair of multiple-fulcrum levers, respective means operatively connecting the latter with said fixed-fulcrum levers, and means for coupling said variable-fulcrum levers with the other of said objects to be separated, said frame having formed therein a plurality of fulcruming points for each of said variable-fulcrum levers.

6. A stripping device of the character described, comprising a member adapted to be suspended from an overhead crane, a frame having an object-engaging portion for coaction with one of two objects to be separated, a pair of fixed-fulcrum levers mounted on said frame and having respective links connecting them with said member, a pair of variable-fulcrum levers each carrying two fulcrum bearing pins, respective links connecting the latter with said fixed-fulcrum levers, and means for coupling said variable-fulcrum levers with the other of said objects to be separated, said frame having a plurality of pairs of notched seats formed therein for coaction with the said fulcrum bearing pins, whereby the mechanical advantage of the assemblage is varied during the stripping stroke of the device.

PEER D. NIELSEN.
